UNITED STATES PATENT OFFICE.

ESSINGTON N. GILFILLAN, OF CHICAGO, ILLINOIS, ASSIGNOR TO THE
GILFILLAN SCALE AND HARDWARE COMPANY, OF SAME PLACE.

DESIGN FOR A SCALE-FRAME.

SPECIFICATION forming part of **Design No. 25,327**, dated **March 31, 1896.**

Application filed April 5, 1894. Serial No. 506,501. Term of patent 7 years.

To all whom it may concern:

Be it known that I, ESSINGTON N. GILFILLAN, a citizen of the United States, residing at Chicago, in the county of Cook and State of Illinois, have invented and produced a new and original Design for Scale-Frames, of which the following is a full, clear, and exact specification, reference being had to the accompanying drawing, forming a part thereof.

10 The said drawing is a perspective view of a scale-frame, illustrating my design.

The leading features of my design consist of a plate A and a standard or upright portion B, having a laterally-projecting arm C, 15 carrying a scale plate or dial D.

The plate A forms the foot of the scale-frame and is arranged in a substantially hori-

zontal position, and from the edge of this plate rises the standard B of frame, from the upper end of which the arm C of frame projects in 20 a substantially horizontal direction. The scale plate or dial D is round or circular and is apparently supported in a vertical plane or upright position at the end of the arm C a short distance above the plate A. 25

Having thus described my design, what I claim as new, and desire to secure by Letters Patent, is—

The design for a scale-frame, substantially as herein shown and described.

ESSINGTON N. GILFILLAN.
